TAICHIRO MASUDA, OF MARYSVILLE, CALIFORNIA

FIGURE POLYCYCLE.

1,226,560.

Specification of Letters Patent Patented May 15, 1917.

Application filed March 8, 1917. Serial No. 162,065.

To all whom it may concern:

Be it known that I, TAICHIRO MASUDA, a citizen of the Japanese Empire, residing at Marysville, in the county of Yuba and State of California, have invented new and useful Improvements in Figure Polycycles, of which the following is a specification.

This invention relates to velocipedes, and more especially to polycycles carrying a figure which in the present case is shown as a toy horse, although of course I do not wish to be limited in this respect; and one object of the same is to improve the general structure by providing adjustable means for mounting an animal figure on the running gear which latter carries the driving and steering wheels and the driving mechanism, so that the jolts and jars incidental to driving the vehicle over a rough road are communicated to the frame rather than to the figure.

Another object is to adapt the frame of the running gear for the reception of other figures than that shown, and to adapt such various figures to the frame.

Other objects will appear in the following specification and claims, reference being had to the accompanying drawings wherein:

30 Figure 1 is a side elevation,

Fig. 2 a plan view with the figure removed.

Figs. 3 and 4 are cross sections on the line 3—3 and 4—4 respectively of Fig. 2.

35 Figs. 5 and 6 are views looking respectively upward and downward on the line 5—6 of Fig. 1.

Fig. 7 is a detail of the connection in one of the limbs of the figure or animal, and

40 Fig. 8 is a detail of the bracket for supporting the animal's foot or hoof.

The running gear of the polycycle in the present instance comprises a frame F having a pair of rear driving wheels R and a pair of front steering wheels S, and carrying the driving mechanism D between them; and the figure is an animal A such as a horse whose limbs or legs L are supported by said framework and whose head H is movable for steering purposes as will be explained. Much of the detailed construction of these several parts is immaterial.

The frame F is preferably made of a single piece of strap iron whose sides are parallel throughout most of their length as

at 1, diverge from each other slightly toward the rear end as at 2, and are again parallel at their rear extremities as at 3, and the side stretches of this piece of metal are integrally connected by a bend 4 at the front of the frame as best seen in Fig. 2, and are connected at various points by bolts through the sides and sleeves 5 on the bolts as usual. I propose that this frame F shall stand about horizontal, to which end the larger rear wheels R have their axle 6 passing through the side bars of the frame, whereas the smaller front wheels S have their axle 7 passing under the frame as seen in Fig. 4. A bolster 8 overlies this axle and may well be made of strip metal of some resiliency, and a spring 9 of the same metal may underlie it as best seen in Fig. 4, the king bolt 10 passing through the bolster and spring and axle as shown, its upper end 70 passing through a U-shaped connection 11 between the side bars of the frame at this point. The steering wheels S are loosely mounted on the extremities of the front axle. So also is one of the rear wheels as 80 indicated at 12, whereas the other is fixedly mounted on the axle as indicated at 13 in Fig. 2. Hence the rear axle must revolve in its bearings in the frame, and as it revolves it drives one of the rear wheels R but the other is loose so that the device may turn corners.

The driving mechanism D includes a shaft 20 journaled through the side bars of the frame near the midlength thereof and having cranks and pedals 21 on its extremities, a driving sprocket 22 fast on this shaft, and a chain 23 connecting it with a driven sprocket 24 fast on the rear axle 6; and to this extent the driving mechanism of this vehicle 95 is similar to that of any rear driven polycycle or bicycle. While this invention has been called a polycycle, I might say that at this point it is not impossible to substitute a single front wheel for the two steering wheels S shown, and by proper adaptation of the steering mechanism yet to be described, the machine would become a tricycle. I prefer, however, to have the running gear mounted on four wheels because it 100 is less liable to accident and this is a consideration in any toy which is to be used by children.

The steering mechanism comprises an upright post 30 journaled near its lower end 113

through a bearing in a bridge 31 which connects the side bars of the frame forward of the driving mechanism as best seen in Fig. 2, and carrying on its lower end a cross head 33 curved slightly as shown. The ends of this cross head are pivotally connected by links 34 with the front axle, the forward ends of the links being shown as attached to the bolster 8 at the points 36 in Fig. 4 although this is a matter of choice. The use of the bolster, with or without the spring beneath it, is to sustain the forward end of the frame F in a plane level with the rear end, but if the front wheels S were made larger there would be no necessity of a bolster and in that case the links would probably be attached directly to the axle or to eyes therein as usual. It follows that when the steering post 30 is turned from side to side the front axle will be adjusted to steer the vehicle.

Referring now more particularly to Figs. 1, 5 and 6, the head H of the animal A is separated on a horizontal line through the neck, and at the point where the two parts meet the contour thereof is preferably circular, or is at least such that the ordinary appearance of the neck is maintained when the head of the animal is in alinement with his body. The steering post forms the axial pivot between these members. It extends vertically upward through and is loosely mounted in the body A, and above the line of division between the body and the head it is continued upward through the latter and threaded at its upper extremity for the reception of a nut 40. In the face of the lower end 41 of the head as seen in Fig. 5 is cut a transverse groove 42, and through the post 30 is passed a pin 43 which is drawn upward into this groove when the nut 40 is tightened up. Finally a washer 44 incloses the post beneath the pin. The face 45 at the upper end of the neck of the body, as seen in Fig. 6, is cut off flat so as to make close contact with or stand very near to the face 41 of the upper member, and a second washer 46 may overlie the face 45 and lie in contact with the upper washer 44 so that the head H may turn easily upon the neck of the body A. When now the nut 40 is adjusted, the upper end of the post 30 is drawn upward into the head until the pin 43 is seated closely within the groove 42, and setting the nut up tight thereafter locks the upper end of the post within the head. Therefore when the child riding on the animal turns the head from side to side, either by hand or by use of the reins as shown, the movement of the head is communicated to the post, and the lower end of the latter turns the front axle and the steering wheels S in a manner which is clear.

I consider this detail of construction important and advantageous, because while it

permits the animal to have the normal function of turning its head from side to side, said movements are transmitted by the post 30 directly to a mechanical steering mechanism located wholly in and carried by the running gear below the animal and not only forming no part of the figure structure but also including no other necessary connection between a part of the figure and a moving part of the vehicle. When the figure is to be removed or replaced with another, it is easily accomplished by removing the nut 40 and pin 43 and drawing the parts of the figure upward, and a new figure may be substituted by a reversal of this operation. When the steering mechanism proper needs cleaning or repair, the mechanic directs his attention only to the parts at the lower end of the post 30 and within the running gear.

I have said that one of the objects of the invention is to permit the substitution of another figure A for that shown. In such new figure the feet or hoofs may not occur precisely where they do in the one illustrated, and adjustments of parts are necessary to make them fit. With this end in view I have shown each leg L as in two members 50 and 51 above the knee joint 52, and I preferably connect the members by securing a wood screw 53 in and along the axis of one member as seen in Fig. 7 and driving it axially into the other member 50, as also shown in dotted lines in Fig. 1. This or an equivalent means of connecting the parts or members 50 and 51 swivelly, will permit the lower portion 54 of the leg below the knee 52 to be swung outward and inward slightly for a purpose yet to appear. In connection with this detail I preferably provide four brackets, best seen in Fig. 8, whereof each is made of pliable strap metal and of substantially the construction illustrated. Each bracket comprises a body 60 of appropriate length and intended ordinarily to stand oblique to the vertical, the lower end of the body being bent slightly on a line 61 to produce an upright ear 62 at its lower extremity, and the upper end of the body being bent slightly on a line 63 to produce a horizontal ear 64 at its upper extremity; and one side of said ear may be bent on a line 65 to produce an upstanding ear 66. All the ears are pierced with holes or more preferably with slots 67 as shown, through which may pass bolts or screws having appropriate washers. It is quite clear that brackets of this or of similar type may be attached to any point in the strap metal frame F. In Fig. 2 a bracket is shown whose slot 67 will be slipped over the bolt 5 which passes through the rearmost sleeve 5, so that the ear 62 will lie against the outside of the right-hand stretch of the frame F, under the nut of said bolt. The same view shows another bracket upstanding from the 130

bend 4 at the front end of the frame F, and in that case the strap metal frame would have to be drilled with a hole through which passes a bolt which passes also through the 5 slot 67. Ordinarily the body portion 60 of the brackets will incline outward from the frame, because the latter is relatively narrow, and the ears 64 at the upper ends of the brackets will stand horizontal. At the 10 right end of Fig. 1, one of these ears is shown as underlying the hoof 68 of the front leg of the animal, and obviously a screw will be passed upward through the slot in this ear and into the bottom of the hoof. A little 15 farther to the left this view shows one of the upstanding ears 66 as disposed behind the next hoof, and here a screw will pass through a slot in this ear and forward into the hoof. It is to be understood that the 20 material of the brackets is pliable to a certain extent, and therefore if the parts may not be properly adjusted by means of the slots 67 in the various ears so that some ear underlies or lies against some portion of 25 each hoof, the strap metal of the brackets can be bent forcibly on any of the lines 61, 63 or 65. Moreover the swivel connection of and between the parts 50 and 51 of each leg 30 of the animal A, permits the setting of his several hoofs laterally with respect to the brackets, whereas the latter are vertically adjustable on the frame by means of the lowermost upright slots 67. Thus the detailed construction of the legs of the animal 35 coacts with the detailed construction of the brackets and their means of adjustable attachment to the frame and to the hoofs, to one end which is that, within certain limits, the animal shown can be replaced by an 40 other whose feet or hoofs would not necessarily occupy the relative position of the one illustrated. With the form of steering mechanism described and shown, it is of course necessary that the post 30 shall rise 45 loosely through an upright hole in the body portion of the animal and shall be fixed in an upright hole in its head portion H, and this necessity emphasizes the advantage of having the various adjustments in the means 50 for mounting the animal or figure on the running gear. Otherwise than as distinctly described, the parts are of appropriate sizes

and materials, and I do not wish to be limited to details further than as is covered by the appended claims.

55

What is claimed as new is:

1. In a figure polycle, the combination with a running gear including a frame carrying driving wheels and steering wheels, the driving mechanism, and the steering 60 mechanism; of an animal figure having four legs, each made in two parts swivelly connected with each other above the knee joint, and brackets connecting the hoofs with the frame of the running gear, as described.

65

2. In a figure toy, the combination with a running gear including a frame mounted on wheels; of a quadruped animal figure, and four brackets, each having an upright ear at its lower end, a horizontal ear at its 70 upper end and an upright ear upstanding from one edge of said horizontal ear and all ears provided with slots, those in the lowermost ear for the reception of means adjustably attaching it to the frame and 75 those in the other ears for the reception of means adjustably attaching them to the hoofs of said figure.

80

3. In a figure toy, the combination with a running gear including a frame mounted on wheels; of a quadruped figure, and four brackets of pliable metal, each having an oblique body, an upright ear at its lower end, a horizontal ear at its upper end, and an upright ear upstanding from one edge of 85 said horizontal ear and all ears provided with openings, those in the lowermost ear for the reception of means attaching it to the frame and those in the other ears for the reception of means attaching either of them 90 to one foot of said figure.

85

4. In a figure toy, the combination with a running gear including a frame mounted on wheels; of a quadruped figure each of whose legs is in two parts above the knee joint, a 95 wood screw fast in one part and extending axially into the other whereby the parts are adjustably connected, and for each leg a bracket of pliable metal having means for adjustably attaching its lower end to the 10 frame and adjustably attaching its upper end to the animal's foot.

95

In testimony whereof I affix my signature.
TAICHIRO MASUDA.
